By W. S. Bellows, Attorney,

UNITED STATES PATENT OFFICE.

EDWARD H. ELDER, OF CHICOPEE, MASSACHUSETTS, ASSIGNOR TO THE
J. STEVENS ARMS AND TOOL COMPANY, OF SAME PLACE.

EXTRACTOR MECHANISM FOR FIREARMS.

SPECIFICATION forming part of Letters Patent No. 663,604, dated December 11, 1900.

Application filed August 24, 1900. Serial No. 27,888. (No model.)

To all whom it may concern:

Be it known that I, EDWARD H. ELDER, a citizen of the United States of America, and a resident of Chicopee, in the county of Hampden and State of Massachusetts, have invented 5 certain new and useful Improvements in Extractor Mechanism for Firearms, of which the following is a full, clear, and exact description.

10 This invention relates to improvements in the extractor mechanism for a shotgun or other firearm of the breakdown class.

The object of the invention is to provide an 15 extractor of entire efficiency which is composed of a minimum of very simply constructed and durable parts, to the end of cheapness, ease of assemblage and adjustment, and freedom from derangement.

The invention consists of the constructions 20 and combinations of parts, all substantially as hereinafter fully described, and set forth in the claims.

Reference is to be had to the accompanying drawings, in which—

25 Figure 1 is in substance a central view through the portion of the gun in which the extractor mechanism is comprised, the breech being shown open, while Fig. 2 is a similar sectional view, but showing the breech closed.

30 In the drawings, A represents the frame of the gun, comprising the forward extension A², to which the bottom lug B of the barrel or barrels is jointed at d, as usual. The bottom lug B under the barrel is provided with the 35 longitudinal bore or socket b, extending therethrough from end to end. The forward end of the bottom lug terminates at a little distance to the rear of the joint-pin d.

C represents the extractor or ejector, the 40 stem f of which is fitted and plays longitudinally in the aforesaid bore b, said stem being of a length less than that of the said bored bottom lug, so that the forward end of the stem terminates somewhat to the rear of the forward end of the bottom lug, leaving the 45 space for occupancy of the spiral spring g, the rear end of which is in bearing against the forward end of the ejector-stem, operating to exert a crowding rearward action against 50 said stem while the forward end of the spring is in abutment against the vertical part h of

the single piece or device D, which comprises the latch or catch for the ejector and also a lever extension by means of which the said catch has its releasing movement imparted thereto. The bottom lug has its forward 55 lower portion recessed at i, and from this recess extends the upwardly-leading aperture j, which communicates with the socket or bore b.

60 The aforesaid device D is constructed in the form of a single integral piece comprising the longitudinally-extending main lower member 10, the right-angularly and upwardly extended lug or arm 12, the extremity of which 65 constitutes the latch to engage in the catch-notch m in the under side of the stem f of the ejector, the upwardly-extending aforementioned abutment member h, the position of which is a short distance to the rear of the 70 forward end of the main bar 10, and the extension 13, projecting forwardly from the upper part of the said abutment portion h. The forward extremity 14 of the lower main portion 10 of the said integrally-formed device 75 has its position beneath the joint-pin d and is pivoted at n to opposite members or cheeks of the bottom lug, between which the forward part of the said device D is fitted.

80 The forward end portion of the frame extension A² has the thickened portion or nose o in advance of the joint-pin and of the upper forwardly-extending member 13 of the device D. This nose is formed with a screw-threaded socket p, in which the screw-plug q 85 is provided, the point or extremity of which screw-plug constitutes an adjustable contact member for the extension or part 13.

85 s represents a limiting-pin screw-threading through a rear portion of the bottom lug and 90 having its point entering in the groove t in the under side of the ejector-stem, this provision serving to prevent the extractor from being thrown out from the socket b in case the gun should be broken down so far as to 95 leave the ejector clear above the breech u.

When the gun is closed from the open position shown in the drawings to the position in readiness for firing, the ejector is by its impingement against the vertical forward face 100 of the breech and in a usual manner forwardly forced to occupy the position of its

ejector proper, C, within the recess *v* and of its stem in such a forward position as to have its catch-notch *m* advanced to a point adjacent the aforesaid catch member 12. The 5 down swinging of the barrel also carries the forward end of the part 13 away from the upper inner end of the screw-plug *q*, so that the device D as a whole may have a swinging movement from its pivotal point of connection 10 with the bottom lug and as insured by the spring *g* in compression between the forward end of the ejector and the rearward vertical face of the upstanding part *h*, so that the catch 12 will engage in the catch-notch 15 *m*. Now, reversely, when the gun is broken down or opened the said integral device D, moving bodily in unison with the barrel bottom lug and relatively to the frame extension *A*² and coming to contact against the 20 abutment-plug *q*, causes after the gun has been sufficiently opened to render the operation of the extractor desirable the swinging of the device D relatively to the barrel-lug, whereby its catch member becomes freed 25 from the extractor-stem, and whereby the extractor may be projected rearwardly by the spring *g*.

I am aware that it is not new in extractor or ejector mechanisms to employ, in combination with the stem of an ejector, a catch or latch movable angularly to engage a catch-notch therein and a lever jointed to the latch and arranged to have its swinging movement imparted thereto by contact against a fixture or immovable part of the frame of the arm, but in such device it appears to have been deemed necessary to construct the latch and its lever separately and to so arrange or organize the parts that the lever has a direct 35 forcing action against the ejector-stem. This mechanism above referred to embodied a greater number of parts than does mine and also a different arrangement thereof and a different manner of their action.

40 It is to be particularly pointed out in this mechanism that the device D, comprising the several members or parts all made as one therewith, serves not only as the latch, but also as the element through which the force 45 to operate to release the latch is transmitted. In this device a single spring is employed—that is, between the end of the ejector and the abutment portion *h* of the device D, which performs the double duty, first, of throwing 50 the ejector rearwardly when the gun is opened and the catch is positively released, and, secondly, of forcing the device D into the position to have its catch 12 engage the catch-notch of the ejector when the gun is closed. 55 The contact-screw *q* may by being moved 60

inwardly or outwardly slightly in the threaded socket *p* therefor have such a location relatively to the device D as to operate the latter for the release of the ejector at any desired stage in the opening movement of the gun. 65

Having thus described my invention, what I claim, and desire to secure by Letters Patent, is—

1. In a breakdown gun, in combination, the gun-frame having at a forward part thereof an abutment as resistant, the barrel having in its bottom lug the longitudinal bore open at the front and rear ends of said lug and having the transverse aperture *j* leading to said bore, the ejector having its stem provided with a catch-notch, the device, D, comprising the bar or lever member 10 having its forward end pivotally supported by the bottom lug, having at its rear end the rigid upward catch extension 12, projecting within said aperture *j*, having at a forward portion thereof the upwardly-extending portion *h* constructed with the forward member 13, the end of which is adjacent said resistant or abutment of the frame, and the spring *g* located in the forward part of said bottom-lug bore and operating upon both the ejector-stem and the said portion *h* of the single device D, substantially as described. 75

2. In a breakdown gun, in combination, the gun-frame having at a forward part thereof the screw-threaded socket *p* and the screw-plug *q* adjustably engaged therein, the barrel hinged to the frame and having in its bottom lug the longitudinal bore open at the front and rear ends of said lug, and having the transverse aperture *j* leading to said bore, the ejector having its stem provided with a catch-notch, the device, D, comprising the bar or lever member 10 having its forward end supported pivotally on the bottom lug below the point of hinge connection of the barrel to the frame, having at its rear end the rigid upward catch extension 12, projecting within said aperture *j*, having at a forward portion thereof the upwardly-extending portion *h* constructed with the forward member 13, over the hinge-point the end of which member is adjacent the end of said screw-plug *q*, and the spring *g* located in the forward part of said bottom-lug bore and operating endwise against both the ejector-stem, and the said portion *h* of the said single device D, substantially as described and shown. 105

Signed by me at Chicopee Falls, Massachusetts, this 21st day of August, 1900.

EDWARD H. ELDER.
